RICHARD PEALE, OF ST. BENEDICT, PENNSYLVANIA, ASSIGNOR TO REMBRANDT PEALE, OF ST. BENEDICT, PENNSYLVANIA.

MINING MACHINE.

Application filed June 23, 1920. Serial No. 391,103.

The invention relates to mining machines, and in certain of its aspects it relates more particularly to novel driving or propelling and actuating mechanisms for the kerf cutting mechanism of machines of the rotary cutter bar type.

Objects and advantages of the invention will be set forth in part hereinafter and in part will be obvious herefrom, or may be learned by practice with the invention; the same being realized and attained by means of instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:—

Fig. 1 is a top plan of a machine embodying the invention;

Fig. 2 is an end elevation, looking at Fig. 1 from the foot, that is, the right hand side of the sheet;

Fig. 3 is a side elevation, looking at Fig. 1 from the right, that is, from the top of the sheet, and showing the machine in one operating position in a coal seam;

Fig. 4 is a horizontal section, looking downwardly, taken on line 4—4 of Fig. 2;

Fig. 5 is an enlarged, fragmentary, sectional, detail, in elevation, taken on line 5—5 of Fig. 4, with certain parts in elevation, showing the cutter drive and one of the winding or snubbing drums for advancing the entire machine;

Fig. 6 is an enlarged, fragmentary sectional detail, in elevation, taken on line 6—6 of Fig. 1, showing a detail of part of the mechanism for advancing the cutter bar;

Fig. 7 is an enlarged, fragmentary, sectional detail, in elevation, taken on line 7—7 of Fig. 1, looking in the direction of the arrows;

Fig. 8 is an enlarged, fragmentary, sectional detail, in elevation, taken on line 8—8 of Fig. 1, looking in the direction of the arrows;

Fig. 9 is a greatly enlarged, sectional detail, in elevation, taken on line 9—9 of Fig.

2, looking in the direction of the arrows, showing the traveling and guiding means and the rotating means for the rotary cutter bar;

Fig. 10 is a section taken on line 10—10 of Fig. 9, looking in the direction of the arrows;

Fig. 11 is an enlarged, sectional detail, in elevation, taken on line 11—11 of Fig. 4, looking in the direction of the arrows and showing the drive for the longitudinal conveyor;

Fig. 12 is a vertical, transverse section through the machine, made somewhat diagrammatic for the sake of clearness, taken substantially on line 12—12 of Fig. 1, showing the devices for rotating the cutter bar as it travels;

Fig. 13 is a vertical, transverse section through the machine, also made somewhat diagrammatic for the sake of clearness, taken substantially on line 13—13 of Fig. 1, just within 12—12, and showing the means for guiding and progressing the cutter bar along its path; and

Fig. 14 is a diagrammatic plan view, showing one manner of applying the machine to the work.

The exemplified embodiment of the invention includes cooperating means or devices for imparting a traveling or advancing motion to a cutter bar, and for imparting at the same time rotary motion to the cutter bar about its own axis.

In such embodied actuating or operating means for the cutter bar, the bar is mounted in suitable holders or bearing blocks, which latter are mounted in guideways spaced apart along the cutter bar, and are thereby adapted to take up the transverse stresses on the bar, and to maintain it in alignment. These holders or bearing blocks are drawn along and slide within the guideways, the cutter bar having connections which impart thereto the requisite rotary motion about its own axis by reason of its movement along its guideway.

Further, and more in detail, as embodied, the bearings or bearing blocks for the cutter bar are slid along their guideways in both directions by means of a line or cable wound in one direction upon a drum and unwound therefrom in the opposite direction, the motion being reversible to give travel

or advancement in either direction to the cutter bar. The shaft or shank of the cutter bar is provided with one or more sprocket wheels meshing with a sprocket chain, which chain travels in the opposite direction from the cutter bar, thereby imparting to the cutter bar the necessary rapid rotation about its own axis.

The path of travel of the cutter bar is determined by the guideways. Whatever the length or direction of the guideways, the flexible controls for the cutter bar, that is, the cable for advancing the bar and the chain for rotating the bar, readily accommodate themselves to a guideway of any shape or length.

In accordance with certain features of the invention, the cutter bar and its actuating mechanism are embodied in a machine designed to make a bottom kerf or undercutting, the machine entering the undercutting, as it is made, and carrying the cutter bar with it into the undercutting, the machine coming to rest in the undercutting. The cutter bar then makes an upward, vertical and then a top horizontal, and then a downward vertical kerf to separate the mass of coal above the undercutting, so that it will fall, or may be easily loosened and be thrown down upon the machine in the undercutting.

The machine is preferably equipped with conveyors, which form very largely the top of the machine inside the frame, whereby as the coal falls or is thrown down, it is automatically conveyed away.

More in detail to the present embodiment, the machine has a flat low frame with a cutter chain running around the outside thereof, making a bottom kerf or undercutting into which the frame is slid to advance the cutter chain to its work. The cutter bar is nested within this frame and enters the undercutting therewith, its guideways and operating means being mounted on the outside end of the frame. The machine has winding means to advance it to its work either in a forwardly or sidewise direction.

Other features of the invention will be set forth in connection with the following detailed description of the present embodiment, and it will be understood that the preceding statements are exemplary and explanatory and are not restrictive of the invention.

As previously stated, the invention in the exemplified embodiment is applied to a machine adapted to cut a bottom kerf, the frame of the machine sliding into this kerf or undercutting as it is made, the top interior of the frame consisting principally of belt or apron conveyors which convey away the broken-down coal.

In the embodied form, a general frame 1 is provided, of general rectangular conformation and provided with rounded corners,

In the exterior vertical face of this frame is provided a guideway 2, in which guideway runs a cutter chain 3, provided with teeth 4 proportioned and arranged to cut a kerf of sufficient height that the frame 1 may slide thereinto.

In the embodied form of driving mechanism for the cutter chain 3 it is driven from a motor 5, which motor is utilized for driving all parts on the machine. In the driving connections for the cutter-chain, a beveled gear wheel 10 is fixed on one end of the shaft of the motor 5. Meshing therewith are two beveled gear wheels 11 and 12 (Figs. 1, 2, 5, and 7), which gear wheels are loose on a shaft 13, journaled in bearings 14 and 15, mounted on the machine frame. Splined on shaft 13 are two clutches 16 and 17, which may be operated to connect shaft 13 to either of the driven beveled-gear wheels 11 and 12, whereby the shaft 13 may be driven in either direction.

These clutches and the shaft 13, in addition to providing a support for the gear wheels 11 and 12, are utilized to press or drive the machine to the work by means of a suitable winding drum, as will be later explained. Fixed to beveled gear wheel 11 is a spur-gear wheel 20, and fixed to beveled-gear wheel 12 is a spur-gear wheel 21. Gear wheel 20 meshes with a gear wheel 23, which is loosely mounted on a shaft 24, journaled in bearings 25 and 26, mounted on the machine frame. Gear wheel 21 meshes with a gear wheel 27, likewise loosely mounted on the shaft 24.

Splined on shaft 24 is a double-jawed clutch 28, adapted to engage with clutching devices on the spur gear 23, or alternatively with like clutching devices on the gear wheel 27, to drive shaft 24 (Figs. 4 and 5) in either direction. Fixed on shaft 24 is a beveled gear wheel or pinion 30, meshing with a beveled gear ring 31 formed or fixed on the top side of a horizontally disposed sprocket wheel 32 (Figs. 1 and 5). Sprocket wheel 32 has its shaft 33 journaled in bearings 34 and 35 in the machine frame, the sprocket wheel teeth 36 meshing with teeth or recesses 37 in the inside face of the cutter chain 2 to drive the chain. It will be understood that when the cutter chain is reversed in its direction of travel, the inclination or direction of the teeth 4 must also be reversed, which can be done by taking off the chain and putting it on the other way about.

Suitable devices are provided for pressing the machine to the work, these devices in the present embodiment operating by means of winding cables which are attached to suitable anchors or screw-jacks positioned in the direction in which the machine is to be drawn or travelled. In the embodied form of said means (Figs. 1, 2, 4, 5, 7 and 14) two winding drums 40 and 41 are fixed on a shaft 130.

42, journaled at 43 and 44 in bearings formed on the machine frame. In the driving means therefor, a geared pinion 45 is fixed on shaft 42, pinion 45 meshing with gear wheel 23, already described (Figs. 1, 4, and 7). This provides for a drive of the drums 40 and 41 in either direction.

Suitable guiding devices are provided for the cables from drums 40 and 41, such as 10 idler pulleys 46, 47, 47^a, 47^b, and 48, positioned at any suitable point on the machine. Pulley 46 is mounted on a shaft 46^a. Pulleys 47, 47^a, and 47^b are at the floor level; pulley 48 is detachably positioned by a pin 15 in any one of a series of holes in the frame 1. The cable 52 running over these pulleys passes over the lower reaches of chains 162 and 163 and between the upper and lower reaches of the conveyor 60. 20 In Fig. 14 jacks or anchors 49 and 50 are shown, likewise arranged at any suitable points, the cables 51 and 52 being attached to the anchors, passing over the pulleys and being wound about the drums 40 and 41. To 25 avoid interference between the machine and the jacks or anchors, when necessary the jacks are secured in diagonal position between the top of the vein or seam and the side wall or rib of the coal, the bottom of 30 the jack being sufficiently high to permit of the cutter chain and frame of the machine passing beneath the jack without interference. With the mechanism for reversing the 35 direction of drive of the cutter chain, and of the winding means, and for reversing the cutter chain itself, the machine will cut in any desired direction, by positioning jacks or anchors, to which winding cables are attached, so that the machine will be pulled 40 by the cables in such direction.

Further, in the present embodied form, the machine is equipped with a conveyor system, occupying the greater part of the top of the frame, whereby after the under cutting has 45 been made and the machine is in the under-cutting, the under-cut coal when it breaks down, or is broken down, falls upon the conveyor or conveyors and is automatically conveyed away by the machine.

50 In the embodied form (Figs. 1, 4 and 14) a longitudinal conveyor extends the entire length of the right-hand side, and for substantially half the width of the machine. In Fig. 4 the top reach of the conveyor belts is 55 broken away to show more clearly the interior of the mechanism. This conveyor 60 comprises an endless belt or apron running over an idler roller 61 (Fig. 4) journaled at 62 and 63 in the machine frame. A driving roller 64 for the conveyor 60, is at the other or outer end, journaled at 65 and 66 in the machine frame.

The driving means for the foregoing (Figs. 1, 2, 4, 8 and 11) comprise a clutch member 67 fixed to a shaft 68 (Figs. 4 and

11) of the roller 64. Cooperating therewith is a clutch member 69, splined for longitudinal movement on a shaft 70, which shaft has one end journaled within the clutch member 67, and is also journaled in bearings 71 and 72 mounted upon the machine frame. Coiled about shaft 70 is a spring 73, in compression between the clutch member 69 and the bearing 71, and pressing clutch member 69 into driving engagement with the clutch member 75 67. The clutch may be thrown off by means of a suitable yoked lever of the usual form (not shown) engaging with an annular groove 74, formed in the hub of the clutch member 69 in the usual manner. Shaft 70 is 80 driven by means of a geared pinion 77 fixed thereon and meshing with a gear wheel 78, fixed to gear wheel 27, which has already been described.

Referring now to the drive for the transverse conveyor, which in the embodied form as shown in Figs. 1 and 4, is located at the upper left-hand part of the machine, the driving mechanism occupying the lower left-hand part. The mechanism is best shown 85 in Figs. 1 and 4, the drive being shown in the latter figure. This conveyor 84 runs over an idler roller 85, journaled at 86 and 87 in the machine frame. At its opposite end, conveyor 84 runs over a driving roller 88, journaled at 89 and 90 in the machine frame.

The driving means therefor comprises a shaft 91 for the roller 90 on which shaft is splined a clutch member 92. Clutch member 100 92 is spring pressed against a cooperating clutch member 93 by means of a spring 94 in compression between the hub of clutch member 92 and a collar 95 fixed on shaft 91. Shaft 91 is journaled at its free end 105 in a bearing 96. Clutch member 92 may be thrown on and off by an actuating lever of the usual type (not shown).

Fixed to clutch member 93, which is loose on shaft 91, is a beveled gear 98, and meshing therewith is a beveled gear 99, which is fast on a shaft 100. Shaft 100 is journaled in bearings 101 and 102 mounted on the machine frame. Fixed also in shaft 100 is a beveled gear 103, with which meshes a 110 beveled gear 104 mounted on a shaft 105. The driving connections for shaft 105 will be later described, as they comprise a part of the drive for certain other mechanisms which will be later described.

The embodied means for cutting the upper kerf, to separate the block of coal, to cause it to either break down of its own weight, or to be readily broken down, and fall upon the conveyors, comprises a rotary cutter-bar which is nested in the frame 1, and which enters the under cutting therewith as the frame travels into the under-cutting as the cutter chain 2 cuts the bottom kerf. The cutter bar is provided with 125 130

bearings or bearing means in which its shank is journaled, the bearing means traveling along a multi-directional or angled guideway, that is, a guideway having reaches 5 transversely disposed with respect to each other, and preferably having two vertical side reaches and in intermediate top horizontal reach, whereby the cutter bar is capacitated to cut an upwardly progressing 10 vertical kerf, turning into a horizontal kerf at the top of the vein, and then turning in to a downwardly progressing kerf toward the undercutting.

Further, as embodied, the mechanism for 15 laterally advancing or feeding the cutter bar comprises winding means which draw or slide the bearing means in which the shank of the cutter bar is journaled along the guideways, just referred to, which determine the path of travel of the cutter bar. As herein embodied, cables are attached from both directions to a pair of bearing blocks, which blocks work or slide in two 20 separate guideways, spaced apart so as to prevent side lash or flexure of the cutter bar, the winding cables winding upon and off of a driven drum, the drum being reversible in its direction of winding, to advance the cutter bar along its pathway, in 25 either direction.

In accordance with one feature of the invention, the means for imparting rotation to the cutter bar about its own axis, comprises devices operating wholly, or in part 30 through, or in conjunction with, the bodily or translational travel or feed of the cutter bar. As embodied, a sprocket wheel or other toothed wheel, or wheels, is fixed to the shaft of the cutter bar, and is in mesh 35 or engagement with a toothed member extended along or adjacent to one, or preferably both, of the guideways for the cutter bar bearings. Specifically, as embodied, two sprocket wheels are fixed upon the shaft or shank of the cutter bar, each of the sprocket 40 wheels meshing with a corresponding sprocket chain, these chains travelling in the guideways in an opposite direction to the direction of travel of the cutter bar. Thus, 45 rotary motion equal to the sum of the forward travel of the cutter bar and of the opposite or reverse travel of the sprocket chains is imparted to the cutter bar about its own axis.

Referring in detail to the specific embodied structure of the means for progressing or travelling the cutter bar along its guideway (Figs. 1, 2, 3, 4, 6, 9 and 10) a cutter bar 115 is provided with cutting teeth 50 116, which may be of any adequate or standard construction. Cutter bar 115 is provided with a shank, or shaft, 117, which is preferably of considerable length to steady and hold the cutter bar against side strains, 55 and against movement transversely to its

axis. Shaft 117 is mounted in two bearing blocks 118 and 119, spaced apart along the shaft, as already described, and for the purposes stated. Shouldered bushings 120 and 121 may be used to sleeve shaft 117 in its 70 bearings 118 and 119.

The bearing blocks 118 and 119 are preferably of spheroidal or oblate form in their dimensions along the guideways, so as to pass readily about the curves at the junctures 75 of the different reaches of the guideways. This form is clearly shown in Figs. 9 and 13. The guideways for the bearing blocks 118 and 119, in which the bearing blocks slide during the progress of the cutter bar in cutting a kerf, or in returning to its original position after cutting a kerf, comprise inferior and superior channels 122 and 123 for the bearing block 118 and like channels 124 and 125 for the bearing block 119. These 80 channels are practically of the shape of a very broad inverted U, as will be seen from Figs. 2, 12, and 13.

These guide the cutter bar in an angled or bent path to make an upwardly progressing 90 vertical kerf, a top horizontal kerf, and a downwardly progressing vertical kerf. The first of these three kerfs starts out at the undercutting by reason of the cutter bar being nested in the frame 1, and the last 95 of them will again connect with the undercutting, unless the mass of coal breaks off in the meantime. The guideways are provided with crossbracing 126 between the channels 124 and 125, and between the channels 125 and 123. The bases of these guideway channels are firmly supported upon and fastened to the main frame of the machine.

As embodied, attached to the bearing block 118 (Figs. 1, 4, 6, 10, and 13) at either 105 side thereof, are the two ends of a cable 128, the cable running through the guideway and the corners of the guideway acting respectively as guiding shoes for the cable. The cable intermediately of its attached ends is 110 wound about a drum 134, so as to simultaneously wind on and pay off therefrom in either one direction or the other, dependent upon the direction of rotation of the drum. Guiding pulleys 135, 136, 137 and 138, are 115 shown for directing the cable between the drum and the guideway.

Drum 134 is loosely mounted upon a shaft 140, journaled in bearings 141 and 142, on the machine frame. For the purpose of rotating the drum, fitted into one end of the drum is a cone clutch 143, splined on shaft 140, and adapted to engage with a coned end of the drum 134 to drive it. An actuating lever 144 for the clutch is fixed to 125 a shaft 145, and has an arm 146, provided with a pin engaging in an annular groove 147 in the cone clutch 143. This lever serves to throw the clutch into and out of driving relation with the winding drum 134. 130

Shaft 140 is driven in a suitable manner and by any suitable connections. As shown, a worm wheel 148 is fixed on shaft 140 and meshing therewith is a worm 149, which is fixed on a vertical shaft 150, journaled at 151 in the machine frame. Fixed also to shaft 150 is a spiral gear pinion 152, with which meshes a spiral gear pinion 153, fixed on shaft 13, previously described. This 10 gives a driving connection operating in either direction from the motor 5 to the winding drum 134.

Referring now to the specific embodied details of mechanism for rotating the cutter bar, embodying the features of invention already described or referred to, two sprocket wheels 160 and 161 are fixed to shaft 117, preferably on the exterior sides of the bearing blocks 118 and 119. These two sprocket 20 wheels mesh (Figs. 1, 9, 10, and 12) respectively with sprocket chains 162 and 163, the sprocket chains, respectively, running in guideways 164 and 165, formed within the channels 122 and 124.

25 The sprocket chains, in accordance with one feature of the invention, are driven in the opposite direction from the direction of travel of the cutter bar while it is cutting the kerf. In the embodied form of means 30 for driving the sprocket chains, driving sprocket wheels 168 and 169 mesh respectively with the sprocket chains 162 and 163 to drive the chains. The sprocket wheels 168 and 169 are fixed on a shaft 170, suitably journaled in the machine frame in 35 bearings 171 and 172. Fixed on shaft 170 is a pair of sprocket wheels 173 and 174, over which run sprocket chains 175 and 176. These chains run also over a pair of sprocket 40 wheels 177 and 179, fixed on the shaft 105, which has been previously described. Shaft 105 is journaled in bearings 180 and 181, mounted on the machine frame. Fixed on 45 shaft 105 is a gear wheel 183, with which meshes a pinion 184, fixed on the shaft of motor 5.

In the embodied form, the cutter bar 115 is nested at the right-hand side of the machine as shown in Figs. 1 and 4, the cutter bar and its shank passing downwardly within the frame 1, alongside the conveyor 60. When the cutter bar is operated it passes upwardly out of its position as described, to cut the kerf prescribed by its guideways, and then, by reversing the winding mechanism, the cutter bar is returned to its place within frame 1.

The invention in its broader aspects is not limited to the particular constructions and arrangements herein shown and described, but departures may be made therefrom within the scope of the accompanying claims, without departing from the principles of the invention and without sacrificing its chief 60 advantages.

What I claim is:—

1. A mining machine including in combination a low, flat frame, a cutting chain extending therearound, a cutter bar nested therein, an angled guideway for guiding the 70 cutter bar in a bent path, means for rotating the cutter bar, and means for impelling the cutter bar along the guideway.

2. A mining machine including in combination a low, flat frame, a cutting chain 75 extending therearound, a cutter bar nested therein, a guideway for guiding the cutter bar upwardly, transversely and downwardly, means for impelling the cutter bar along its guideway, and means for rotating the 80 cutter bar.

3. A mining machine including in combination a low, flat frame, a cutting chain extending therearound, a cutter bar nested therein, an angled guideway for guiding the 85 cutter bar in a bent path, means including a driving chain traveling along the guideway for rotating the cutter bar, and means for impelling the cutter bar along the guideway. 90

4. A mining machine including in combination a low, flat frame, a cutting chain extending therearound, a cutter bar nested therein, a guideway for guiding the cutter bar upwardly, transversely and downwardly, means for impelling the cutter bar along 95 its guideway, and means including a driving chain traveling along the guideway for rotating the cutter bar.

5. A mining machine including in combination a low flat frame, a guideway for a cutter bar, having two vertical reaches and a horizontal reach connecting the two vertical reaches, a cutter bar movable up one vertical reach of the guideway, across the horizontal reach and down the other vertical reach, a power driven chain travelling up one vertical reach of the guideway, across the horizontal reach and down the other vertical reach of the guideway, for rotating 100 the cutter bar, and means for moving the mining machine bodily sidewise for pressing the cutter bar to the work. 105

6. A mining machine including in combination a low flat frame, a guideway for a cutter bar, having two vertical reaches and a horizontal reach connecting the two vertical reaches, a cutter bar movable up one vertical reach of the guideway, across the horizontal reach and down the other vertical reach, a power driven chain travelling 115 up one vertical reach of the guideway, across the horizontal reach and down the other vertical reach of the guideway, for rotating the cutter bar, and means travelling in 120 the said guideway and connected to the cutter bar for moving it bodily sidewise to press it to the work.

7. A mining machine including in combination a low flat frame, a guideway for a 130

cutter bar, having two vertical reaches and a horizontal reach connecting the two vertical reaches, a cutter bar movable up one vertical reach of the guideway, across the horizontal reach and down the other vertical reach, a power driven chain travelling up one vertical reach of the guideway, across the horizontal reach and down the other vertical reach of the guideway, 5 for rotating the cutter bar, means for moving the whole mining machine bodily for pressing the cutter bar to the work, and flexible, power driven means, travelling in said guideway, for pressing the cutter bar 10 to the work.

8. A mining machine including in combination a low flat frame, a cutting chain extending therearound, a guideway for a cutter bar, having two vertical reaches and a horizontal reach connecting the two vertical reaches, a cutter bar movable up one vertical reach of the guideway, across the horizontal reach and down the other vertical reach, a power driven chain travelling up 20 one vertical reach of the guideway, across the horizontal reach and down the other vertical reach of the guideway, for rotating the cutter bar, and means for moving the mining machine bodily sidewise for 25 pressing the cutter bar to the work.

9. A mining machine including in combination a low flat frame, a cutting chain extending therearound, a guideway for

a cutter bar, having two vertical reaches and a horizontal reach connecting the two vertical reaches, a cutter bar movable up one vertical reach of the guideway, across the horizontal reach and down the other vertical reach, a power driven chain travelling up one vertical reach of the guideway, across the horizontal reach and down the other vertical reach of the guideway, for rotating the cutter bar, and means 35 travelling in the said guideway and connected to the cutter bar for moving it bodily 40 sidewise to press it to the work.

10. A mining machine including in combination a low flat frame, a cutting chain extending therearound, a guideway for a cutter bar, having two vertical reaches and a horizontal reach connecting the two vertical reaches, a cutter bar movable up one vertical reach of the guideway, across the horizontal reach and down the other vertical reach, a power driven chain travelling 50 up one vertical reach of the guideway, across the horizontal reach and down the other vertical reach of the guideway, for rotating the cutter bar, means for moving the whole mining machine bodily for pressing the cutter bar to the work, and flexible, power driven means, travelling in said guideway, for pressing the cutter bar to the work. 55

In testimony whereof, I have signed my name to this specification.

RICHARD PEALE.
